UNITED STATES PATENT OFFICE.

HERBERT CHASE, OF FOREST HILLS, NEW YORK.

TOY BUILDING.

Application filed March 6, 1925. Serial No. 13,431.

My invention relates to toys for the amusement of children.

The object of my invention is to provide a house or building made of portions which 5 may be assembled and disassembled by a person unskilled in mechanics, and that may be made of thin sheet metal or similar suitable material by punch and die processes.

A further object is to provide a construction consisting of parts that are interchangeable, and of completed units that may be assembled to provide a building of larger size 10 by joining the selected units together.

The specific features of novelty will be 15 herein after set forth and set forth in the claims.

Referring to the drawings which form a part of this application,

Fig. 1 is a front elevational view of a toy 20 building illustrating my invention.

Fig. 2 is an end elevational view of the construction shown in Figure 1, mounted on lower structure to provide a two story house.

25 Fig. 3 is a perspective view of the walls, gables, roof, floor, sides and end walls used in building the construction illustrated in Figures 1, 2, 4 and 5.

Fig. 4 is a cross sectional view on an enlarged scale to illustrate the means used for 30 holding the parts together and the manner of assembling.

Fig. 5 is an illustrational view, shown partly in section, to show two similar units 35 joined together end to end to provide a longer building.

Fig. 6 is a view of the glass portion of the window.

Fig. 7 is a view of the window casing and 40 blinds.

Fig. 8 is a view of the parts shown in Figures 6 and 7, in assembled relation.

Fig. 9 is a longitudinal section view 45 through the construction shown in Figure 8, taken on line 9—9 thereof.

Fig. 10 is a perspective view of a flower box, when used as such as shown in Figure 1, or as a balcony when made higher and wider as shown in Figure 2.

50 As before stated, the several parts are preferably made of sheet metal which is blanked out and pressed into form to provide the gables and frame portions.

55 A, indicates the base sheet which serves as a floor and which is provided with flanges A' at each side which extend at right angles

to the plane surface of the floor and each of which is provided with holes A² located at pre-determined points so as to register with the respective holes, B' formed in the lower 60 ends of the side sheets B and end sheets C, hereinafter referred to as walls. D and D' indicate the bolts and nuts used for holding the adjacent parts together. The end walls C are each provided with flanges C' extending vertically the full height of the wall and of double thickness of the wall, formed integral by bending the end portions back on itself as illustrated at C² in Figure 3, to form smooth edges C³ and also to stiffen and 65 strengthen the wall C and serve to better brace the walls B. The walls B and C are also stiffened by the window and door casings, which are reinforced by turning the edge portions B²—B² etc. back onto the inner side of the wall as shown in Figure 3, and which construction also provides smooth 70 edged casements B³, as will be readily understood. The gables E are formed with inwardly extending flanges E' having holes E² 75 formed therein to register with the holes F² formed in the roof portions F. The gable portions are duplicates of each other and are also the roof portions. Each roof portion 80 forms one half of the roof of a single room, and is provided with a projecting flange F' which extends from the middle of a portion to the inner edge of a flange E', the roof portions being bolted together as illustrated at D³ in Figure 4. The roof portions are 85 each provided with a flange F⁴ at each end and with a turned up lower edge F⁵ to form a gutter, the sharp ends of which are protected by the lower end of the flange F⁴ as 90 shown at F⁵ in Figure 3. The chimneys G are provided with flanges G' at the two lower 95 sides, one of which has a hole G² therethrough, and held by the same bolt and nut unit which is used to hold the roof portion to the flange E'. When it is desired to unite 100 two rooms end to end as illustrated in Figure 5, the roof portions of each room are shifted longitudinally relative to the side walls until the end flanges F⁴ abut the face of the respective gable, as illustrated in Figure 5, and to permit this movement the flanges E' of each gable is provided with two holes E²—E² respectively spaced apart the distance necessary to permit the flange to 105 abut the gable, or if desired, the metal between the holes could be removed to provide a slot of the proper length, which would 110

serve the same purpose. The distance between the end of the flange F' at F^6 , and the flange F^4 must be great enough to permit this shift, exclusive of the width of the flange 5 E' which occupies a portion of this space.

By leaving out the end walls C shown in Figure 5, the two rooms may be formed into a single room, as will be readily understood.

In Figure 2 I have illustrated a two story 10 construction made from the same kind of side and end walls, bolted together in superimposed relation, and a third story could be added in the same manner if desired.

The window casing and blind construction 15 illustrated in Figures 7 and 9 comprises an exposed display portion H having inwardly turned flanges H' — H' etc. on all four sides, and four holes indicated by H^2 respectively which register with the four holes formed 20 adjacent each window casing in the side and end walls, and is held on the walls by four nut and bolt units H^2 respectively between which the glass window I is supported, the upper and lower flanges H' serving to support the window at the top and bottom ends thereof. The window I is of glass or other suitable material and the frame outline for the panes is painted thereon as indicated by I' . The moon shaped crescents H^3 are 25 formed by punching out the metal or may be painted on the surface of the casing to indicate a window blind.

The flower box, J and balcony K constructions are alike except in their proportions 30 and are made from a single piece of metal bent to form the same after being blanked, and are attached to the wall by the same bolts which serve to hold the bottom end of the casing H . A light bulb may be placed 35 in a room of the house and the light shine through the window, which may be colored if desired, to give a pleasing appearance to the building. It is obvious from the foregoing description that many modifications as

to form and dimensions may be made without departing from the invention disclosed. 45

Having thus described my invention I claim as new:

1. In a toy building a flooring a wall formed of sheet material having an opening 50 therein, the edges adjacent said opening being bent back upon the wall to provide smooth exposed portions, and to stiffen the wall adjacent thereto, said wall being detachably connected to the flooring at the top and 55 bottom, and a window casing attached to said wall in detachable relation thereto, and a window pane supported in said casing.

2. A toy building comprising a flooring side and end walls, the side walls being 60 duplicates of each other, and the end walls being duplicates of each other, each wall having holes spaced apart at pre-determined distances adjacent the top and bottom edges and arranged to register with the holes 65 formed in the other walls and in the flooring used in the building to provide a structure having one or more stories, the side and end walls of which are interchangeable.

3. A toy building comprising a flanged 70 flooring, side and end walls, the side walls being duplicates of each other, and the end walls being duplicates of each other, each wall having holes spaced apart at pre-determined distances adjacent the top and 75 bottom edges and arranged to register with the holes formed in the other walls and the flanges of said flooring used in the building to provide a structure having one or more stories, the side and end walls of which 80 are interchangeable, and gables having holes located adjacent their lower edge spaced to register with the holes formed in the top of the end walls.

In testimony whereof, I, HERBERT CHASE 85 have signed my name to this specification, this fourth day of March, 1925.

HERBERT CHASE.
